(**) Term: **14 Years**

(57) **CLAIM**

(21) Appl. No.: **29/194,982**

The ornamental design for a closing tool for foil food container, as shown and described.

(22) Filed: **Dec. 4, 2003**

DESCRIPTION

(51) LOC (7) Cl. **08-05**
(52) U.S. Cl. **D8/14**
(58) Field of Search D8/14, 21, 40,
D8/43, 88, 105; 81/3.09, 3.08, 3.55

(56) **References Cited**

FIG. 1 is a top side perspective view of a closing tool for a foil food container showing our new design therefor;
FIG. 2 is a top plan view thereof, the bottom being identical;
FIG. 3 is a side elevational view thereof, all other sides being identical; and,
FIG. 4 is a sectional view taken along line 4—4 of FIG. 2 to reveal the contours of the design.
